[57] ABSTRACT

[22] Filed: July 19, 1974

A device capable of tightening or loosening the fastener bolts on a concrete mold successively in an automatic fashion without necessitating intermittent feed of the mold. A bolt driver unit is mounted on a manipulator and is positioned for bolt tightening or loosening operation only when a fastener bolt is detected upstreamside of the manipulator but is retracted whenever any rib, tire or other radial projection on the mold is detected. For detection, an appropriate object recognition system is usable which utilizes image information taken by an industrial television camera. The device can serve molds practically of every make owing to its construction and mode of operation.

AUTOMATIC FASTENING DEVICE WITH BOLTS FOR CONCRETE MOLDS

BACKGROUND OF THE INVENTION

This invention relates to the bolt fastening of concrete molds or formworks of the type used in forming concrete piles or the like concrete products and is intended to provide a device which is operable automatically to tighten or loosen the fastener bolts on such concrete molds.

The bolt-fastening operation must be carried out under various work conditions. Among others, there are a wide variety of molds to be served, which differ from each other in size and configuration; and no intermittent feed is allowed for the work because of the high note of production required. Fastener bolts are usually arranged on the mold at irregular intervals. Molds of the type described not only include members such as ribs and tires, which extend radially outward beyond the fastener bolts, but are tapered with opposite end diameters differing from each other.

Under these conditions, it has previously been very difficult to mechanize the bolt driving operation to any substantial extent and, in actual practice, the operator has been required to stand in an appropriate position along the line of mold flow and work manually to tighten or loosen the fastener bolts on the mold, keeping time with the advancing movement thereof. In addition, so-called impact wrenches normally used in such operation are of considerable weight, rendering it very hard for the operator to work continuously for any extended period of time.

SUMMARY OF THE INVENTION

Under these circumstances, the present invention has its object the provision of an automatic bolt-fastening device for concrete molds of the type described which in performance stands comparison favorably with human labor.

Another object of the present invention is to provide a device of the character described which includes a detecting section designed to detect the configuration and position of the concrete mold with its different components and a working section or manipulator carrying a bolt driver unit operable to tighten or loosen the fastener bolts on the mold in travel.

Other objects and advantages of the present invention will be apparent from the following description when taken in conjunction with the accompanying drawings, which illustrate one preferred embodiment of the invention.

BRIEF DESCRIPTION OF THE DRAWINGS

In the drawings:

FIG. 1 is a perspective view illustrating the general arrangement of a mold for forming concrete piles and a bolt-fastening device embodying the principles of the present invention;

FIG. 2 is a block diagram illustrating the electric control circuitry of the bolt-fastening device;

FIG. 3 is a side view, partly in section, of the bolt driver supporting structure of the device shown in FIG. 1;

FIG. 3a is a cross-sectional view taken substantially along the line IIIa — IIIa in FIG. 3;

FIG. 4 is a perspective view of the detecting section of the bolt-fastening device;

FIGS. 5 and 5a diagrammatically illustrate respective television images successively taken of a bolt sustainer block;

FIG. 6 is an explanatory diagram of an image-recognizing frame formation;

FIG. 7 illustrates the overlapping relationship of a block image with the image recognizing frame, shown in FIG. 6;

FIGS. 7a and 7b are diagrams explaining the principle of image recognition and showing the manner in which respective calculations indicated vary with the position of the block image relative to the recognizing frame; and

FIG. 8 is a circuit diagram of the image processing system.

DESCRIPTION OF THE PREFERRED EMBODIMENT

Referring to the drawings and first to FIG. 1, reference numeral 1 generally indicates a pile mold, which is moved in a direction indicated by the arrow by means of a carriage, not shown. The mold 1 has fastener bolts 2 arranged on its side to be tightened or loosened, and carries ribs 3 and tires 4, both shown only one, as indicated at 3 and 4, respectively, and which extend radially outward from the mold body usually to form a trouble in operation, the tires 4 being generally larger than ribs 3 in radial extent.

The ribs 3 have respective external diameters varying gradually with their axial location on the mold 1, which is tapered, while tires 4 have all the same external diameter irrespective of the mold taper. As shown, the faster bolts 2 are each mounted on the mold side by means of a bolt sustainer block 13 so that they may not tilt or fall off the mold.

For bolt fastening or unfastening operation, various work conditions must be taken into account as pointed out before. First, the bolts 2, ribs 3 and tires 4 are not only irregular in order of arrangement on the mold but are arranged, respectively, at irregular intervals axially of the mold. Further, molds flowing along one and the same line of operation are usually not of the same configuration, differing one from another in external diameter, axial length and in spacing and order of work members. In addition, such molds are required to be fed continuously but not in any intermittent fashion because of the high tact of operation required and substantial mold weight.

Under these conditions, the working section of the bolt-fastening device, which takes the form of a manipulator 12 in the embodiment shown, is required to be synchronized with movement of the mold 1 for bolt tightening or loosening operation and includes a bolt driver unit arranged so as to be retracted clear of any approaching rib 3 or tire 4.

Further, the detecting section of the bolt-fastening device is required to be of a versatile non-contacting type which is capable of detecting bolts 2, ribs 3 and tires 4 at all times without fail irrespective of their irregularities in spacing or order and need not be retracted in any manner as to clear the ribs and tires.

Accordingly, the present invention employs an object recognizing device for detection of bolts 2 and ribs 3, which utilizes an industrial television camera 9 as an input means. For detection of tires 4, however, the device of the present invention employs an appropriate tire detector 10, for example, in the form of a micro-

switch as the television camera 9 can hardly be focused for tires 4, which have all the same external diameter irrespective of the mold taper and a radial extent much larger than that of ribs 3 and bolts 2 particularly at locations close to the smaller diameter end of mold 1.

Further, the embodiment illustrated includes a side detector 8 which serves to set the respective detector units for bolts 2, ribs 3 and tires 4 at a predetermined distance from the mold side each time a mold 1 is fed to work station as molds may differ from each other in external diameter. As will be understood, the detector units once set are moved forward or backward with respect to the mold 1 according to the taper thereof.

Operation of the device of the present invention will next be described together with the details of construction and arrangement of the device.

First, when a mold 1 being moved axially in a continuous fashion reaches the station where the device of the invention is installed, a detector 6, for example, in the form of a photoelectric tube or a microswitch, operates to move the side detector 8 a definite distance toward the adjacent side of the mold 1 by the aid of an associated ON-OFF cylinder 7. On the other hand, a shaft S, carrying cylinder 7, television camera 9, and tire detector 10 in the form of a microswitch, is driven forward until the side detector 8 is brought into contact with the adjacent side of the mold 1, when the S-shaft comes to stop. In this manner, the television camera 9 and tire detector 10, together forming the detecting section of the present device, are finally positioned and then the side detector 8 alone is retracted under the action of cylinder 7.

The position of the detector section relative to the mold is subsequently corrected by advancing or retracting the S-shaft with respect to the tapered mold 1 according to the amount of its axial movement as determined by a pulse generator mounted on the mold carriage. In this manner, the detecting section can be held at a predetermined distance from the adjacent side of mold 1 irrespective of the axial displacement of the latter.

Next, a visual image processor device used to detect bolts 2 and ribs 3 will be described with reference to FIGS. 5 et seq.

In this embodiment, bolt sustainer block 13 is employed as an object to be recognized for detection of the bolt 2 and, when the block 13, moving in the direction indicated by the arrow in FIG. 1, is caught by the television camera 9, it forms an image such as shown in FIG. 5 at a certain instant and subsequently as shown in FIG. 5a. In these figures, the hatched area represents the dark region of the television picture, the remaining area representing the light region thereof. As will readily be understood, such television picture can be obtained by giving different brightnesses or colors to the object of recognition, i.e., the bolt sustainer block 13, and its background. For recognition of such image input, a row of four closely adjoining regions A, B, C and D are defined within the area of image frame, as shown in FIG. 6. Regions A and D at the opposite ends and intermediate regions B and C, respectively, have the same horizontal width and the sum of the horizontal widths of the intermediate regions B and C is equal to the horizontal width of the image of bolt sustainer block 13. With end regions A and D, the image value therein determines the area corresponding to the dark background while, with intermediate regions B and C,

the image value therein determines the area corresponding to the light object. The areas determined in this manner are represented by a, b, c and d, respectively, for regions A, B, C and D and the following calculations are performed.

$$S = a + b + c + d$$

$$P = a - b + c - d$$

It is to be noted that, when the image of bolt sustainer block 13 lies exactly on the regions B and C in combination, both S and P become zero ($S = 0, P = 0$), and that, when the image of block 13 lies slightly to the right, S and P are positive and negative, respectively, that is, $S > 0$ and $P < 0$. Oppositely, when the image of block 13 lies slightly to the left, S and P are both positive, that is, $S > 0$ and $P < 0$.

Such relationship between the position of the image of block 13 and the values of S and P will be readily understood from FIGS. 7, 7a and 7b. FIG. 7 illustrates the position of the image of block 13 relative to the row of regions A, B, C and D at an instant when the horizontally medial point or center of the image lies at the point indicated by the block dot. FIGS. 7a and 7b respectively illustrate the manner in which S and P vary with movement of the image center along the row of regions A, B, C and D.

Now it is assumed that the recognition output is to be produced at the instant when the image of bolt sustainer block 13 passes across the boundary between the intermediate regions B and C, that is, at the instant when P changes in sign from negative to positive.

However, where an image input is obtained through a television camera as in this case, such image input is obtained once in each field period. Because of this, the image of block 13 effects intermittent motion and hence P cannot attain a value of zero. In addition, S may not be reduced to zero as the bolt sustainer block 13 does not always produce an image having a horizontal width that is equal to the sum of the horizontal widths of intermediate regions B and C.

In order to meet these conditions, the image processing system is so arranged as to produce a recognition output at the instant when P has increased to zero or further to a positive value as long as S lies below an appropriate predetermined level.

In FIG. 8, which illustrates the circuit arrangement of the image processing system, reference numeral 36 indicates a circuit for changing the image input signal from the television camera 9 into binary form; and 37 indicates a sampling circuit provided to horizontally disperse the binary image input from the circuit 36, which is continuous in time.

Reference numerals 39, 40, 41 and 42 indicate gate circuits for respective regions A, B, C and D, and 38 indicates a gate signal generator giving a gate signal to the gate circuits 39, 40, 41 and 42 through respective terminals A, B, C and D. As will readily be understood, the gate signal can be easily obtained by utilizing the timing signal for horizontal sampling and the horizontal synchronizing signal of television camera 9.

Reference numerals 43 and 44 indicate OR circuits receiving inputs from gate circuits 39, 40 and from gate circuits 41, 42, respectively; 45 indicates another OR circuit receiving inputs from the OR circuits 43 and 44; 46 indicates a counter for counting the number of output pulses of the OR circuit 45; and 47 indicates an up-down counter for addition of the output of gate circuit

43 and subtraction of that of gate circuit 44. Assuming that these counters 46, 47 are reset at the start of scanning, it is to be understood that the outputs of counters 46, 47 represent $S = a + b + c + d$ and $P = a - b + c - d$, respectively, at the end of scanning.

Reference numeral 48 indicates a digital comparator designed to produce an output 1 when the count number of counter 46 is within a predetermined range; and 49 indicates a register for storing the sign of up-down counter 47 in the preceding image scanning. Reference numeral 50 indicates a judgment circuit producing an output only when the output of register 49 is negative and the outputs of up-down counter 47 and digital comparator 48 are zero or positive and 1, respectively. It is arranged so that the output of up-down counter 47 is stored in the register 49 after the operation of judgment circuit 50 has been completed.

In the manner described above, a timing output can be obtained with respect to a passing object and, in this case, the output represents a recognition of a bolt sustainer block 13 as imaged in FIG. 5 or 5a. Such recognition output is fed to the manipulator control each time a bolt 2 flows in. As will readily be understood, ribs 3 can be recognized in the same manner by the provision of another set of circuits 38 et seq with appropriate settings therefor.

Further, it is to be understood that the detector 10 is so arranged that an appropriate recognition output is produced and fed to the manipulator control each time a tire 4 flows in.

The manipulator control is so designed that, upon receiving any of such detector signals, it converts the detector signal into a positional information and stores such information together with the kind of the work detected in an associated memory. The positional information is changed according to the movement of mold 1 and remains stored until the operation required for the work (that is, tightening or loosening of bolt 2 or retraction for ribs 3 or tire 4) is completed. Circuit arrangement of the memory is illustrated in FIG. 2.

Referring to FIG. 2, when a detector signal S_0 , corresponding to a work member such as bolt 2, rib 3 or tire 4, is received, the output S_2 of counter 26, which is counting the number of output pulses S_1 from the pulse generator mounted on the mold carriage, is read into a first-in first-out type shift register 27 together with the kind of the work member detected. Subsequently, the work member enters the range of movement of manipulator 12 and, when the latter has completed its operation as previously read in, that information is shifted to the last stage register under the direction S_3 from sequence circuit 32. Then, work signal S_4 is put into the sequence circuit 32 and, in case the work is a bolt 2, the difference between the output S_2 of counter 26 and the positional information S_5 from the register is calculated in the subtraction circuit 28 under a preset direction S_9 and the result is read into the preset counter 29. In this case, however, as the value of the output S_7 of preset counter 29, which corresponds to the distance between the work and the detector therefor, must vary with movement of the work, the gate circuit 30 is operated to open under the follow-up direction S_8 to allow passage of output pulse S_1 from the pulse generator mounted on the mold carriage.

In this manner, output S_7 at all times indicates the position of the work or bolt 2 and this makes it possible to enable the manipulator 12 to operate on the work

while following its movement by feeding back the position signal S_9 of the manipulator 12 to the servo control therefor. It is to be understood that the signal S_9 represents the distance of manipulator 12 from the detecting section.

Referring again to FIG. 1, the manipulator 12 forming the working section of the device illustrated includes a shaft T extending in the same direction as that in which mold 1 proceeds, another shaft H extending horizontally at right angles to the direction in which molds 1 proceeds, and a further shaft V carrying a bolt driver unit 18 to serve the purpose of raising and lowering the unit 18.

Both T and V shafts are required to be able to stop at any position desired and are each formed as a servo shaft that obtains feedback position information from a pulse generator, resolver or the like device. The construction of the V shaft and bolt driver unit 18 will next be described with reference to FIGS. 3 and 3a.

The bolt driver unit 18, adapted to be raised and lowered by the V shaft, should be held for operation in a position exactly aligned with the bolt 2 but, since it is impossible in practice to obtain perfect alignment therebetween, it must be so designed as to accommodate a certain range of misalignment, accordingly, in the design shown in FIG. 3a, the driver unit 18 is supported by a structure including two pairs of support rails 23 and 24 which extend at right angles to each other to allow the driver unit to move sidewise in either direction for smooth sliding engagement with the bolt 2.

Referring again to FIG. 1, reference numeral 16 indicates a feeler unit provided beneath the forward end of the H shaft for exact positioning of the manipulator relative to the bolt 2. As shown in FIG. 4, the feeler unit 16 is composed of two operating elements 19, 20 and two detectors taking the form of microswitches 21, 22, and is arranged so that, as it comes close to the bolt 2, the operating elements 19, 21 are brought slowly into contact with the bolt, causing operation of detectors 21, 22 to complete the positioning of the driver unit 18.

Description will next be made of operation of the manipulator 12.

Assuming that the manipulator 12 is located midway of the T shaft, as shown in FIG. 1, it is started to move at high speed toward the bolt 2 as soon as the latter enters the range of movement of the T shaft. Subsequently, when the manipulator 12 has come close to the bolt 2, the T shaft is synchronized with the moving mold 1 on the ON-OFF cylinder 15, secured to the H shaft, is actuated to extend the feeler unit 16 forward while on the other hand the H shaft is driven forward by the servo cylinder 14. As the result, the feeler 16 is brought into contacting engagement with the bolt sustainer block 13 and the H-direction 22 is actuated causing the T and H shafts to stop.

In order to stop the T shaft, the gate 30 is closed under the follow-up direction S_8 shown in FIG. 2. Subsequently, the T-direction detector 21 of the feeler unit 16 is operated with continued movement of the mold 1. Incidentally, if the relative speed between the T shaft and mold 1 is too high, the pulse signal S_1 may conveniently be demultiplied during that period for input to the preset counter 29; and, if the relative speed is too low, the counter 29 may conveniently be formed as an up-down counter and be downed.

In this manner, the manipulator 12 is finally and accurately positioned relative to the bolt 2 and the T shaft again starts to move in synchronism with the movement of mold 1. Simultaneously, the V shaft is caused to descend, enabling the bolt driver unit 18 to tighten or loosen the bolt 2, as the case may be, and is raised after driver operation has been completed.

In this connection, the cylinder 15 is actuated to retract the feeler unit 16 immediately after the positioning has been completed in order to keep the feeler 16 free from any mechanical vibration during the bolt tightening or loosening operation.

Upon completion of such bolt tightening or loosening operation, a shift direction such as indicated at S_3 in FIG. 2 is produced to read out the next stored information and the H shaft is retracted according to that information. That is to say, the H shaft is retracted a little if the read-out information is of a bolt 2; slightly more if it is of a rib 3; and further more if it is of a tire 4. Also, in this case, the T shaft is synchronized with the movement of mold 1 to keep the bolt driver unit 18 clear of the rib 3 or tire 4 during the retracting movement of the H shaft.

Such changing in amount of retraction of the H shaft makes it possible to increase the tact of operation to a substantial extent. However, in cases where the next work is a rib 3 or a tire 4, shift direction S_3 is again issued upon completion of the retracting movement of H shaft in order to read out the succeeding stored information.

The above-described sequential operation is effected by input of the kind of work S_4 (FIG. 2) and respective step signals S_{11} into the sequence circuit 32, as indicated in FIG. 2. Only, any detailed explanation of the circuit construction of the circuit 32 is believed to be unnecessary as it can be realized by ROM or other known technique.

It will be appreciated from the foregoing that accord-

ing to the present invention the bolt tightening and loosening operation on molds for forming concrete piles or the like can be fully mechanized and an automatic bolt fastening device has been provided which has, among others, the following advantages:

1. It has realized automatic bolt driving operation for fastener bolts on molds for concrete piles or the like for the first time in the art.

2. It can tighten or loosen the fastener bolts on the mold successively without necessitating any interruption in movement of the mold.

3. It is relatively simple in construction just with a simple application of a television camera for recognition of moving objects.

15 Numerous alterations of the structure herein disclosed will suggest themselves to those skilled in the art and all such modifications which do not depart from the spirit of the invention are intended to be included within the scope of the appended claim.

What is claimed is:

1. An automatic bolt-fastening device for molds for forming concrete piles or the like, comprising a manipulator arranged for movement relative to the mold and carrying a bolt driver unit operable to tighten or loosen the fastener bolts on the mold, detector means arranged upstream of said manipulator with respect to the movement of the mold relative thereto to detect the fastener bolts and radially projecting members of the mold with the aid of an image information taken by an industrial television camera, feeler means arranged on said manipulator for feeling engagement with the fastener bolt detected, the arrangement being such that said bolt driver unit is accurately positioned for bolt tightening or loosening operation only when a fastener bolt is detected by said detector means and is moved into a position clearing any of the radially projecting members of the mold when such member is detected.
